UNITED STATES PATENT OFFICE.

FINIS McLEAN, OF VALLEY JUNCTION, IOWA.

RAILWAY-TIE PLATE.

1,226,096.

Specification of Letters Patent. Patented May 15, 1917.

Application filed October 7, 1915. Serial No. 54,676.

To all whom it may concern:

Be it known that I, FINIS McLEAN, a citizen of the United States, and resident of Valley Junction, in the county of Polk and 5 State of Iowa, have invented a certain new and useful Railway-Tie Plate, of which the following is a specification.

The objects of my invention are to provide a railway tie plate especially designed 10 for use in connection with concrete ties, whereby the rail engaging means are firmly • and immovably held within the concrete tie and are not likely to become broken loose from the tie by the vibration and wave-like 15 motion of the rail due to the passing of heavy trains over it.

A further object is to provide a tie plate in which a rail may be firmly and securely 20 attached, in a quick, easy and convenient manner.

A further object is to provide a tie plate of this character in which the spreading of rails is positively prevented by having the outer edges of the rail flanges engaged by 25 lugs formed integral with the tie plates, and in this connection it is my object to provide means for firmly securing the inner edges of the rail flanges to the tie plates, said means for securing said inner edges being 30 capable of adjustment to fit rails of different sizes, and also being capable of being detached quickly and easily without injury to the tie plate or the rail engaging member, so that when thus quickly removed it 35 may be replaced.

My invention consists in the construction, arrangement and combination of the various parts of the device, whereby the objects contemplated are attained, as hereinafter more 40 fully set forth, pointed out in my claim, and illustrated in the accompanying drawings, in which:

Figure 1 shows a longitudinal sectional view through a concrete railway tie having 45 my improved rail plates associated therewith, and also showing rails on the plates.

Fig. 2 shows a top or plan view of the reinforcing member of the ties and my improved tie plates attached thereto.

Fig. 3 shows an end elevation of my improved tie plate connected with the tie reinforcing plate.

Fig. 4 shows an enlarged, detail sectional view illustrating the detachable rail engaging flange for the inner edge of the rail flange, the dotted lines in said figure illus-

trating the manner in which by a change in the shape of this rail engaging flange the device may be adapted for rails of different kinds or sizes, and

Fig. 5 shows a top or plan view of one end of a railway tie having my improved tie plate connected therewith, for illustrating the relative widths of the tie and the tie plate.

Referring to the accompanying drawings, I have used the reference numeral 10 to indicate the concrete tie. This is preferably made of two parts, one part being directly under each rail. These two parts are connected together in such a manner as to avoid the possibility of the spreading of the rails in a manner hereinafter described.

Arranged in about the central portion of each of the concrete tie ends is the reinforcing member 11. This is preferably made of a flat sheet of metal extending from a point near the outer end of the tie to a point spaced apart from the inner end of the tie. This plate is then extended upwardly at 12 80 to a point above the tie and then again horizontally at 13. I also preferably provide the plate 11 with a series of openings 14 through which the concrete material may pass so that the material above and below the plate will be bonded together.

In order to connect the two tie members with each other I provide the flat metal connecting bar 15, which extends under the parts 13 and is connected therewith by the 90 bolts 16.

One of the important features in connection with this part of my device is that by having the reinforcing bars 11 and the connecting bar 15 formed of flat metal of considerable width, and by having the connecting bar 15 arranged above the tie, this connecting bar is held out of contact with the earth or cinders or other road ballast, so that it will not be so quickly rusted or corroded as would be the case were it embedded in a road ballast material, and also so that it may be easily accessible for the application of paint or other preserving material.

Furthermore, by having four bolts 16 arranged in these flat wide plates, the two ends of the concrete tie are firmly held in line with each other, so that I attain the material advantages of a single concrete tie extending under both rails and avoid the expense 110 of the central portion of such tie.

The body of my improved tie plate com-

prises a flat central portion 17 having formed therein two rail engaging lugs 18 near the outer end of the tie plate, which lugs are an integral part of the tie plate 5 and are shaped to fit against and overlap the outer edge of the rail. The outer end of the body portion 17 is extended downwardly at 19 and then outwardly at 20, and is bolted to the reinforcing member 11 by the 10 bolts 21. The inner end of the body portion 17 extends downwardly at 22 and then horizontally inwardly at 23 and is connected by bolts 24 with the reinforcing member 11.

When a tie is being cast this tie plate is 15 embedded in the tie with only the body portion 17 of the tie plate above the surface of the tie, hence the bolts 21 and 24 are always firmly held in position. Furthermore, by having a solid body of concrete or any suitable 20 material between the body portion 17 of the tie plate and the reinforcing member 11, and also between the two upright members 19 and 23, it is obvious that none of the metal members below the surface of the tie 25 may move in any direction, because in order to do so the parts of the tie would be subjected to crushing strains, and it is well known that concrete material has very great strength in resisting crushing strains.

30 My improved means for detachably and adjustably connecting the inner edges of the rail flange with the tie plate is as follows: The numeral 25 indicates a rail engaging plate having a part to lie flat on top of the body portion 17, and then a part extending upwardly and toward the center of the rail, said latter part being shaped to fit the rail flange. This plate is provided with bolt 35 openings near its outer end.

40 The body portion 17 of the tie plate is provided with slots 26 open at the side edges of the tie plate, as clearly shown in Fig. 2, and these slots receive the bolts 27 which have been passed through the rail engaging 45 plate 25. The head of the bolt 27 is placed beneath the tie plate body portion 17, there being a suitable recess 28 formed in the concrete for this purpose.

If it should be desired to remove a rail, 50 the operator simply removes the nuts 29 at the upper ends of the bolts 27 with a wrench, or as is the quite common practice a large hammer is used to break off the upper end of the bolt with the nut. Then the plate 25 55 may be lifted up and the bolts may then be driven out with a hammer through the ends of the slots 26. This obviously may be done

very quickly and easily and is also done without any injury whatever to any part of the tie plate. Then when the rail is replaced 60 it can be set down flat on top of the inner end of the tie plate and then shoved out until its outer edge is engaged by the lugs 18. Then new bolts 27 may be placed in position by sliding them through the slots 26 65 and the plate 25 may then be replaced with the said bolts passed through the openings therein and nuts 29 may be applied on the upper ends of said bolts.

If it should be desired to use a rail of different size, the operator may use all of my improved tie plate except the plate 25 and may place the rail in position then drive the lugs 18 with a hammer to position fitting the outer edge of the rail flange, and then 70 he need only substitute new plates 25 to fit the inner edges of the rail flanges, or he may, if he desires, place the old plates 25 in position and shape them by hammering.

In adjusting my improved tie plates for 75 radical changes in the size of the rails, it may be necessary to move the outer lugs 18 outwardly. If this is necessary I provide means whereby it may be accomplished by having the connecting member 15 provided 80 with a series of bolt openings 30, so that the bolts 16 may be placed in any one of these openings, thereby effecting an adjustment of the outer ends of the tie plates relative to 85 each other, so that rails of any size may be 90 accommodated.

I claim as my invention:

An improved railway tie plate comprising 95 two flat metal reinforcing members designed to be embedded in concrete, each having one end extended upwardly and designed to project above the concrete, a flat metal connecting piece detachably and adjustably secured to the upper ends of the reinforcing members and capable of holding said reinforcing members exactly in line with each other, flat metal rail engaging members designed to rest above the concrete in which the reinforcing members are embedded, said rail engaging members having portions extended downwardly and fixed to the said reinforcing members, and means on said rail engaging members for engaging and supporting rails.

Des Moines, Iowa, October 2, 1915.
FINIS McLEAN.
